PAPERBOARD BERRY BOX

James R. Choate, St. Albans, Vt., assignor to Riverside Manufacturing Company, Inc., Murfreesboro, N.C., a corporation of North Carolina

Filed Aug. 2, 1957, Ser. No. 675,854

1 Claim. (Cl. 229—34)

The present invention relates to paperboard berry boxes, and more particularly to such boxes which are reinforced to equal or surpass the strength of prior art wooden berry boxes.

The primary object of the invention is to provide a paperboard berry box having its upper edge reinforced to withstand horizontal and vertical pressures applied thereto.

Another object of the invention is to provide a berry box having the above characteristics which is formed from a single folded blank.

A further object of the invention is to provide a paperboard berry box which is inexpensive to manufacture, simple to use and fill, and which will withstand exceedingly hard usage without becoming damaged thereby or permitting the contents thereof to be spilled or damaged.

A further object of the invention is to provide a paperboard berry box with a rim of sufficient strength to withstand pressure as generated in the process of heat sealing a transparent film to the outer inclined area of the box rim, to form a transparent cover over the box contents.

Other objects and advantages will become apparent in the following specification when considered in the light of the attached drawings, in which:

Figure 1 is a perspective view of the invention.

Figure 2 is an enlarged fragmentary vertical cross-section taken along the line 2—2 of Figure 1 looking in the direction indicated.

Figure 3 is a plan view of the blank from which the box illustrated in Figure 1 is formed.

Figure 4 is a fragmentary enlarged perspective view of the details of the upper corner construction.

Figure 5 is a fragmentary inside perspective view of the upper corner construction.

Figure 6 is an enlarged fragmentary horizontal cross-section taken along the line 6—6 of Figure 5, looking in the direction of the arrows.

Referring now to the drawings in detail wherein like reference characters indicate like parts throughout the several figures, the reference numeral 10 indicates generally a berry box constructed in accordance with the invention.

The box 10 is illustrated in Figure 1 in erected position with the blank from which it is formed being shown in Figure 3. The box 10 includes a bottom wall 11 having parallel opposite side edges 12 and 13 joined by parallel opposite side edges 14 and 15 extending perpendicularly therebetween.

A side wall 16 has its bottom edge integrally joined at 12 to the bottom wall 11. A side wall 17 identical to the side wall 16 is integrally joined at 13 to the bottom wall 11. A side wall 18 is integrally joined at 14 to the bottom wall 11 and a side wall 19 identical to the side wall 18 is integrally joined at 15 to the bottom wall 11.

The side walls 18 and 19 are of identical construction

2

and each include upwardly and outwardly tapering side edges 20, 21. The side walls 18 and 19 each have an outwardly sloping upper end panel 22 integrally joined thereto along a fold line 23. A reinforcing panel 24 is integrally joined to the panel 22 along a fold line 25.

Flaps 26 are integrally joined to the reinforcing panels 24 along a fold line 27 and has an elongated glue tab 28 secured thereto along a fold line 29. The fold lines 14, 15, 23, 25, 27 and 29 are all parallel to each other, 10 as best illustrated in Figure 3.

The side walls 16 and 17 are identical to each other and have outwardly and upwardly sloping tabs 30, 31 integrally secured to the opposite side edges thereof along fold lines 32, 33, respectively. The side walls 16 and 17 are provided with outwardly sloping panels 34 integrally joined thereto along fold lines 35. Reinforcing panels 36 are integrally joined to the panels 34 along fold line 37.

The panels 34 are provided at their opposite ends with 20 corner tabs 38, 39, while the reinforcing panels 36 are provided with oppositely extending corner tabs 40, 41. An elongated mounting tab 42 is integrally joined to the panels 36 along a fold line 43 and has an elongated glue tab 44 joined to the opposite edge thereof along 25 a fold line 45. The fold lines 12, 13, 35, 37, 43 and 45 are all parallel to each other as seen in Figure 3.

The corner tabs 40, 41 are curved at 46 to facilitate the formation of the corner construction in assembling the berry box. A plurality of ventilating perforations 30 47 are arranged along the fold lines 32, 33, for reasons to be assigned.

The berry box 10 is erected by folding the side walls 16, 17, 18 and 19 to a generally upright outwardly sloping position with the reinforcing panels 24, 36 folded 35 downwardly at an angle thereto, as best illustrated in Figure 2, so that the glue flaps 28, 44 can be secured to the box 10 with the flaps 26, 42 extending horizontally locking the reinforcing panels 24, 36 in position.

The flaps 30, 31 are bent at right angles to the side 40 walls 16, 17 and have the side walls 18 and 19 glued thereto in overlying relation. The tabs 40, 41 are inserted between the reinforcing panels 24 and their adjacent panels 22 and are glued to the inner face of the reinforcing panels 24.

45 The tabs 28, 39 are engaged against and glued to the opposite ends of the panels 22, as best illustrated in Figure 6.

In erecting the box 10, the upper portions of each of the walls 16, 17, 18 and 19 are completely formed before 50 the adjacent walls are joined and the arcuate corner 46 of the tabs 40, 41 permit the tabs 40, 41 to be swung into final position without binding.

As will be noted from Figure 2 in the drawings, the 55 panels 22, 34 are arranged at a slightly divergent angle to the side walls 16, 17, 18 and 19 adding strength to the upper edge of the box 10.

Having thus described the preferred embodiment of the invention, it should be understood that numerous structural modifications and adaptations may be resorted to 60 without departing from the scope of the appended claim.

What is claimed is:

A paperboard berry box comprising an integral blank having a rectangular bottom panel, a plurality of side panels integrally joined to said bottom panel and extending upwardly therefrom, means extending between and connecting adjacent edges of the adjacent side panels, a reinforcing panel integrally joined to the upper edge of each of said side panels and lying in a flat plane extending upwardly and outwardly at an angle from the flat 65 plane of said side panels, a second reinforcing panel integrally joined to the upper edge of each of said first

panels and extending downwardly and outwardly therefrom, said second reinforcing panel having the same height as said first reinforcing panel, a third reinforcing panel integrally joined to the lower edge of each of said second panels and extending horizontally therefrom toward the upper edges of said side panels, and an elongated glue tab integrally formed on and depending perpendicularly from the side of each of said third reinforcing panels adjacent said side panels, each of said tabs engaging against and being fixedly secured to a respective one of said side panels closely adjacent the upper edge thereof, means securing said reinforcing panels to adjacent reinforcing panels at the corners of said box, said first, second and third reinforcing panels forming sub-

stantially an isosceles triangle in cross-section, whereby vertical pressure applied on the top edges of said box will be evenly distributed between said first and second reinforcing panels.
